UNITED STATES PATENT OFFICE.

ROBERT C. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed June 13, 1921. Serial No. 477,045.

To all whom it may concern:

Be it known that I, ROBERT C. Osgood, a citizen of the United States, residing at Claremont, in the county of Sullivan and State of New Hampshire, have invented certain new and useful Improvements in Mining Machines, of which the following is a full, clear, and exact specification.

My invention relates to mining machines.

10 It has for its object to provide an improved, compact, effective and readily adjustable take-up mechanism especially adapted to use on flexibly fed machines of the room and pillar type, and improved power 15 connected controlling mechanism whereby the take-up mechanism may be readily adjusted when used to angle the machine during cutting. A further object of my invention is to provide an improved feeding mechanism adapted to be controlled in such a 20 manner as to enable the movement of the machine to be controlled both conveniently and easily by an operator at the machine.

While my invention may be embodied in 25 various forms, in the accompanying drawings I have shown for purposes of illustration one embodiment which the same may assume in practice.

In these drawings,—

30 Fig. 1 is a side elevation of a machine equipped for cutting from right to left, the take-up being shown in a plurality of positions.

Fig. 2 is a view partially in plan and 35 partially in horizontal section, the view being taken on planes corresponding to the portions of the line 2—2 in Fig. 1.

Fig. 3 is a partial sectional view, the section being taken on line 3—3 of Fig. 2.

40 Fig. 4 is a detail sectional view showing the slide for the take-up.

Fig. 5 is a detail section on line 5—5 of Fig. 2.

Fig. 6 is a diagrammatic view showing 45 the mechanism in operation and cutting from right to left.

In this illustrative construction, I have shown a mining machine of a standard room and pillar type comprising a frame 1 having 50 a cutter bar 2 and a cutter chain 3 movable about the latter, the machine being adapted to be moved over the mine bottom on a usual shoe 4 by flexible feeding mechanism, herein including a feed chain 5 guided by cooper-

ating idlers 6 and 7 at opposite ends of the 55 frame and adapted to be fed by the mining machine motor 8 through improved feed operating and controlling mechanism, hereinafter described, which is in turn operatively connected between the motor and a later 60 ally extending feed operating member 9.

In my improved construction, a bevel pinion 10 is operatively connected with the rear end of the shaft 11 of the motor and meshes with a horizontal bevel gear 12 suitably 65 journaled on a vertical axis in rear of the motor and herein at its under side operatively connected through a suitable clutch mechanism 13 (diagrammatically illustrated) with a cutter chain driving sprocket 14. 70 Above this gear 12 and disposed coaxially therewith is a worm 15 connected to an inner concentric shaft 16 through a usual friction clutch mechanism 17. This worm 15 in turn meshes with a worm gear 18 fixed to and rotatable with a transversely extending shaft 19 journaled in the frame 1 and operatively connected with a transverse shaft 75 hereinafter described and driving the feed operating member 9. As shown, the shaft 19 has pinions 20 and 21 on its opposite ends. Of these pinions, the member 21 meshes directly with a larger gear 22 carried on a sleeve 23 freely rotatable on a transverse feed operating shaft 24 to one end of which the 80 feed operating member 9 is fixed. The pinion 20, on the contrary, meshes with a small intermediate pinion 25 suitably journaled on the frame and this pinion in turn meshes with a larger gear 26, similarly rotatable 85 with a sleeve 27 journaled on the other end of the shaft 24. As shown, these two sets of gearing are also adapted to be selectively connected to the shaft 24 in such a manner 90 as to drive the same at different speeds in opposite directions, a clutch member 28 splined to the shaft being disposed between the inner ends of the sleeves and connectible with either through a usual clutch controlling mechanism including a lever 29.

Operatively disposed with relation to the feed operating member 9 is a cooperating idler member 30, the member 30 acting to direct the feed chain relative to the feed operating member and to hold the feed chain in the desired relation thereto. As shown, this member 30 is disposed above the feed operating member and slightly in advance 105

thereof. An additional cooperating chain guiding member 31 of smaller diameter may also be provided in rear of the member 30 and the member 9, and between the member 5 30 and the rear idlers 7. In my improved construction, the member 30 is also adjustable in such a manner as to control the tension of the chain, and therefore, the angular position of the machine, the same being preferably, as herein, operatively connected to the motor under the control of the operator.

Referring more particularly to the construction shown in Fig. 2, it will be observed that the transverse shaft 19 has fixed 15 thereto at a point adjacent the gear 20, a bevel gear 32 which in turn meshes with a bevel pinion 33 carried on the rear end of a longitudinally disposed shaft, 34, in turn carrying on its front end a similar bevel 20 pinion 35 meshing with oppositely disposed bevel gears 36 and 37 each freely rotatable on a transverse shaft 38 herein journaled on the frame above the armature shaft. As shown herein, a clutch member 39 is also 25 splined to the shaft 38 at a point between the gears 36 and 37 and adapted to connect either gear to the shaft as desired, and thereby rotate the shaft 38 in either direction. As shown, the shaft 38 also carries at 30 its outer end a worm 40 meshing with a co-operating worm-gear 41 in turn carried in non-rotative relation thereto on the front end of a longitudinally disposed threaded member 42 rotatable at its rear end in a flanged block 43 carrying the member 30 and longitudinally movable in a recess or slot 44 in the side of the frame. By this construction, it will be observed that 35 through proper manipulation of the clutch member 39, as through a suitable clutch controlling mechanism including a lever 45, the member 30 may be made to move forward or backward relative to the member 9 and thereby take up or release the slack in the feed chain 5.

In the operation of my improved mechanism, the feed chain 5 is threaded relative to the front idler 6 and the elements 9, 30, 31 and 7 in the manner shown in Fig. 1. 50 When it is desired to vary the angle of the machine, the member 30 is adjusted relative to the member 9 in such a manner as to draw in or feed out the rear end of the feed chain, and thereby cause the angle of the bar to be varied relative to the work in a well-known manner. During this operation, it will be observed that it is only necessary for the operator to move the control member 45 in order to cause the member 30 to be moved 55 by power relative to the member 9, movement of the member 45 in one direction causing the member 30 to move forward relative to the frame and to draw in the rear end of the chain and lengthen the portion 60 thereof between the members 9 and 7,

thereby swinging the frame and bar toward the other side, while movement of the member 45 in the opposite direction causes the member 30 to lengthen this portion of the chain and thereby swing the bar back toward its perpendicular relation to the face. Obviously, due to the feeding mechanism provided including the improved variable speed transmission mechanism, the machine 70 may also cut and be moved about the mine 75 at different speeds as usual, my improved feeding mechanism being of simple, compact and powerful form and controllable through the control member 29 in such a manner as to rotate the member 9 slowly 80 when the latter is driven through the gears 20, 22, and to rotate the member more rapidly in a reverse direction when the same is driven through the gears 21, 25 and 26.

While I have in this application specifically described one form which my invention may assume in practice, it will be understood that this form of the same is shown for purposes of illustration and that the invention may be modified and embodied 90 in other forms without departing from its spirit or the scope of the appended claims.

What I claim as new and desire to secure by Letters Patent is:

1. In a mining machine, a frame slidable on a mine bottom during cutting, a feed operating member thereon, a flexible feed member engaging said feed operating member and extending in opposite directions from opposite ends of said frame, and take-up means rectilinearly movable longitudinally on the frame adjacent said operating member and operative to effect angling of said machine frame without changing the point from which the feed operating member leaves the frame.

2. In a mining machine, a frame slidable on a mine bottom, a feed operating member rotatable on a transverse axis thereon, a flexible feed member engaging said member and extending in opposite directions from the opposite ends of said frame, and take-up means rectilinearly movable on said frame adjacent said operating member.

3. In a mining machine, a feed operating member, a cooperating idler adjacent the same and rotatable on a parallel axis, a flexible feed member engaging said members, and means including a cooperating idler movable in a straight line extending generally perpendicular to the working face for varying the length of the flexible member between said first mentioned elements.

4. In a mining machine, a feed operating member rotatable on a horizontal axis, a cooperating idler adjacent the same and rotatable on a parallel axis, a flexible feed member engaging said members, and means including a cooperating idler for varying the length of the flexible member between

said first mentioned elements while said flexible feed member is under tension throughout its effective length.

5. In a mining machine, a frame slidable on a mine bottom, feed driving mechanism thereon including a vertically disposed feed operating member and a flexible feeding member extending in opposite directions from the opposite ends of said frame, a vertically disposed idler adjacent said operating member, and means operatively connected to said driving mechanism for adjusting said idler bodily relative to said feed operating member.
15. 6. In a mining machine, a frame slidable on a mine bottom, feed driving mechanism thereon including a feed operating member rotatable on a transverse axis and a cooperating flexible feeding member extending in opposite directions from the opposite ends of said frame, a cooperating idler adjacent said feed operating member, and means operatively connected to said driving mechanism for adjusting said idler bodily relative to said feed operating member.

25. 7. In a mining machine, a frame, feeding mechanism thereon including a laterally disposed feed operating member and a laterally disposed idler member each rotatable about a fixed horizontal axis, a feed chain cooperating with said feed operating member and also engaging said idler, and means for varying the length thereof between said members while said chain remains under tension throughout its effective length.

35. 8. In a mining machine, a frame slidable on a mine bottom, feeding mechanism thereon including a laterally disposed feed operating member and a laterally disposed idler member each rotatable about a fixed horizontal axis, a feed chain cooperating with said feed operating member and also engaging said idler and extending in opposite directions from the opposite ends of said frame, and means for varying the length thereof between said members while said chain remains under tension throughout its effective length.

45. 9. In a mining machine, a feed operating member rotatable on a transverse axis, an idler member adjacent the same and rotatable on a parallel axis, a flexible feed member engaging said members, an idler rotatable on a parallel axis and engageable with said feed member between said first mentioned members, and means for adjusting said last mentioned idler relative to said feed operating member.

55. 10. In a mining machine, a feed operating member rotatable on a horizontal transverse axis, a flexible feeding member engageable therewith, driving mechanism for said feed operating member, and a cooperating idler engaging said flexible feeding member and adjustable relative to said feed operating

member but rotatable on a parallel axis and movable in opposite directions by said driving mechanism.

65. 11. In a mining machine, a frame slidable on a mine bottom, feeding mechanism thereon including a vertically disposed feed operating member, a flexible feeding member cooperating with the latter extending in opposite directions from the opposite ends of said frame, an idler engaging said flexible member, a stationary guide sheave beyond said idler in terms of flexible feeding member disposition, and means for adjusting said idler longitudinally of said frame including an idler supporting block slidable on said frame.

75. 12. In a mining machine, a frame slidable on a mine bottom, feeding mechanism thereon including a laterally extending feed operating member, a flexible feeding member cooperating with the latter extending in opposite directions from the opposite ends of said frame, an idler engaging said flexible member, a stationary guide sheave beyond said idler in terms of flexible feeding member disposition, and means for adjusting said idler longitudinally of said frame including an idler supporting block slidable on said frame and a threaded member rotatable to adjust said block.

85. 13. In a mining machine, a frame slidable on a mine bottom, feeding mechanism thereon including a feed operating member rotatable on a transverse axis and a flexible feeding member extending in opposite directions from the opposite ends of said frame, a cooperating adjustable idler adjacent said operating member and rotatable on a transverse axis and movable in a rectilinear path, and power driven means for adjusting said idler in either direction relative to said feed operating member.

95. 14. In a mining machine, a frame, feeding mechanism thereon including a feed operating member rotatable on a transverse axis, a cooperating adjustable idler adjacent the same also rotatable on a transverse axis and movable in a rectilinear path, and power driven means for adjusting said element including a clutch for controlling the direction of movement thereof.

105. 15. A room and pillar mining machine slidable on a mine bottom and having flexible lateral feeding means including flexible feeding portions extending in opposite directions from the opposite ends of said machine, and feed operating and rectilinearly movable take-up mechanism cooperating with said portions and disposed on the advancing side of said machine and operative to produce controlled lateral feeding.

115. 16. A room and pillar mining machine slidable on a mine bottom and having flexible feeding means including flexible feeding portions extending laterally in opposite di-

- rections from the opposite ends of the frame, and means cooperating therewith including a feed operating member, a guide sheave and a rectilinearly moving take-up engaging said flexible feeding means between said sheave and said operating member, the reeving of said flexible feeding means around said three members lying in a single plane.
17. A room and pillar mining machine 10 slideable on a mine bottom and having flexible feeding means including flexible feeding portions extending laterally in opposite directions from the opposite ends of the frame, and means cooperating therewith including a feed operating member, a guide sheave and a rectilinearly moving take-up engaging said flexible feeding means between said sheave and said operating member, the reeving of said flexible feeding means around 15 said three members lying in a single plane extending longitudinally of the machine frame.
18. A room and pillar mining machine 20 slideable on a mine bottom and having flexible feeding means including flexible feeding portions extending laterally in opposite directions from the opposite ends of the frame, and means cooperating therewith including a feed operating member, a guide sheave and a rectilinearly moving take-up engaging said flexible feeding means between said sheave and said operating member, the reeving of said flexible feeding means around 25 said three members lying in a vertical longitudinally extending plane.
19. A room and pillar mining machine 30 slideable on a mine bottom and having flexible lateral feeding means including flexible feeding portions extending in opposite directions from the opposite ends of said machine, and feed operating and takeup mechanism cooperating with said portions and disposed on the advancing side of said machine and operative to produce controlled 35 lateral feeding.
20. A room and pillar mining machine 40 slideable on a mine bottom and having flex-
- ible lateral feeding means including flexible feeding portions extending in opposite directions from the opposite ends of said machine, and feed operating and takeup mechanism cooperating with said portions and disposed on the advancing side of said machine and including a feed operating member rotatable on a transverse axis and an adjustable takeup member.
21. A room and pillar mining machine 45 slideable on a mine bottom and having flexible lateral feeding means including a continuous flexible feeding member presenting flexible feeding portions extending in opposite directions from the opposite ends of said machine, and feed operating and takeup mechanism cooperating with said portions and disposed on the advancing side of said machine and operative to produce controlled lateral feeding.
22. A room and pillar mining machine 50 slideable on a mine bottom and having flexible lateral feeding means including a continuous flexible feeding member presenting flexible feeding portions extending in opposite directions from the opposite ends of said machine, and feed operating and takeup mechanism cooperating with said portions and disposed on the advancing side of said machine and including a feed operating member rotatable on a transverse axis and an adjustable takeup member.
23. A room and pillar mining machine 55 slideable on a mine bottom and having flexible lateral feeding means including flexible feeding portions extending in opposite directions from the opposite ends of said machine, and feed operating and takeup mechanism cooperating with said portions and disposed on the advancing side of said machine and including a feed operating member rotatable on a transverse axis and an adjustable takeup member.
24. A room and pillar mining machine 60 slideable on a mine bottom and having flexible lateral feeding means including flexible feeding portions extending in opposite directions from the opposite ends of said machine, and feed operating and takeup mechanism cooperating with said portions and disposed on the advancing side of said machine and including an adjustable power moved takeup member movable to control 65 said receding portion.
- In testimony whereof I affix my signature.
- ROBERT C. OSGOOD.
